United States Patent Office

Des. 176,104
Patented Nov. 22, 1955

176,104

COIN BANK

Albert N. Brooks, Chicago, Ill.

Application February 17, 1955, Serial No. 34,560

Term of patent 7 years

(Cl. D34—11)

Fig. 1.

Fig. 2.

Fig. 3.

Fig. 1 is a side elevation of a coin bank, showing my new design;

Fig. 2 is a top plan view of the same coin bank; and Fig. 3 is a front elevation of the same coin bank.

I claim:

The ornamental design for a coin bank, substantially as shown.
